RADIO SOCKET

Scipione M. Del Camp, Maywood, Ill., assignor to
 Cinch Manufacturing Corporation, Chicago, Ill.,
 a corporation of Illinois

Application August 20, 1935, Serial No. 37,021

1 Claim. (Cl. 173—328)

My invention aims to provide improvements in electrical socket members and relates particularly to so-called radio tube sockets.

In the drawing which illustrates a preferred embodiment of my invention:

Figure 1 is an end view of the center member for a socket;

Fig. 2 is a side elevation of the member shown in Figure 1;

Fig. 3 is a vertical section through the member shown in Fig. 2 viewed from the right;

Fig. 4 is a vertical section through one form of socket member for the reception of a radio tube or other member having rod-like contacts;

Fig. 5 is a section through another form of socket member;

Fig. 6 is a bottom plan view of the socket shown in Fig. 4;

Fig. 7 is a bottom plan view of the socket shown in Fig. 5;

Fig. 8 is a section taken on the line 8—8 of Fig. 6 showing how an implement inserted through the center member is prevented from engaging the contact members; and

Fig. 9 is a side elevational view of a portion of the lower end of a member to be engaged with the socket member.

In the drawing I have shown an improved socket structure for radio and like sockets where the part to be attached to the socket (for instance a radio tube) has a projection for locating the proper projecting contacts or pins with the proper pin-receiving contacts of the socket. The sockets may be of different styles such as shown by Figs. 4 through 7.

My improved socket is formed of two plates of insulating material, which I will term a top plate 1 and a bottom plate 2, and includes a plurality of contact-receiving members 3 of any well known construction assembled with the plates in any well known manner. The top plate 1 has a series of apertures 4 (Fig. 8) preferably arranged in a circle and in alignment with contact-receiving apertures 5 in the bottom plate 2 through which the contacts 3 project, as shown in Figs. 6, 7 and 8.

In the center of the top plate 1 I have provided a relatively large hole 6 in alignment with the same size hole 7 in the bottom plate 2, as best shown in Figs. 4 and 5. These holes are relatively large to accommodate the passage of a projection 10 on a radio tube or other device for engagement with the socket. Such a projection is shown in Fig. 9 and it is made large for strength.

In conjunction with the holes 6 and 7 in the

plates 1 and 2 I have provided a hollow central member 8 which serves several important functions. It is preferably made of metal and has a flute 9 along one side providing a locating member to receive the rib 10 (Fig. 9) on the projection 10a thereby to locate the prongs 11 (Fig. 9) for entrance into the apertures 4 and the contacts 3. As is well known to those skilled in the art the proper prongs 11 must be engaged with predetermined contacts of the socket since they are wired to certain circuits in a radio set or other apparatus. Another important function of the member 8 is to prevent short-circuiting by entrance of a metal instrument (Fig. 8) (such as a screw driver) through the central holes in the 15 socket. This is prevented by the apron 12 formed as an extension of the member 8 below the bottom plate 2, as shown in Figs. 4, 5 and 8. This apron 12 is long enough so that the greatest angle an instrument may take passing through the 20 member will prevent engagement with the contacts 3, as shown by Fig. 8.

The member 8 also acts as a rivet to hold the two plates 1 and 2 together. It has a preformed shoulder 13 (Figs. 1, 2 and 3), near the upper 25 end of the apron 12, which bears against the under side of the bottom plate 2 and the other end of the member 8 is turned outwardly to form a flange 14 bearing against the upper face of the top plate 1, all as shown in Figs. 4 and 5. Thus 30 the parts are secured together and the member 8 may provide the only means holding the parts together, as shown by the two types of sockets illustrated. Instead of having the flange 14 extend from the flute 9 I have formed a notch 15 35 in the upper end of the part 8 (Figs. 1 and 2) which eliminates the flange 14 at that point and leaves a part of the notch 15 exposed (Figs. 4 and 5) so that the rib 10 will more easily find its way into the flute 9. The member 8 also acts as a 40 means to prevent relative rotation of the plates and preferably provides the only means for that purpose to reduce the socket to a minimum of parts. To accomplish this result I have made the apertures 6 and 7 the same shape as the 45 cross-sectional shape of the member 8. Thus the flute 9 extends into notches 16 and 17 in the plates 1 and 2 respectively to interlock the parts against relative rotation. This keeps the apertures 4 in alignment with the apertures 5. The 50 member 8 also reinforces the plates 1 and 2 adjacent to the apertures 6 and 7 so that they will not be broken by pressure from the rib 10 before it has been turned to registry with the flute as might be the case without the member 8. 55

The apron 12 is left open at the lower end because of the fact that the upper end or flange 14 may be rolled over while a setting tool is held against the under side of the shoulder 13, as will be understood by those skilled in the art of setting rivets. This insures proper attachment of the parts with the possibility of breakage reduced to a minimum.

My improved socket is strong, durable, simple 10 in construction and is particularly adapted for use with the new, so-called, metal tubes which are being used for radio reception.

While I have illustrated and described a preferred embodiment of my invention, I do not wish 15 to be limited thereto, because the scope of my invention is best defined by the following claim.

I claim:

A socket comprising an insulating base of gen-

erally flat shape and having a central hollow substantially cylindrical portion with the ends of said hollow substantially cylindrical portion extending beyond the upper and lower faces of said base, the lower extending end thereof being longer than the other extending end thereof, 5 clips located laterally of said hollow cylindrical portion, each of said clips having an end portion thereof fixedly secured to said base and another end portion thereof extending below said base 10 to an extent greater than said lower extending end of said hollow cylindrical portion, said clips being so spaced laterally from said hollow cylindrical portion as to be guarded thereby from contact with the usual straight tools inserted 15 through the cylindrical portion.
